UNITED STATES PATENT OFFICE

ROLAND A. FURLONG, OF ROCHESTER, NEW YORK, ASSIGNOR TO THE YAWMAN & ERBE MANUFACTURING COMPANY, OF ROCHESTER, NEW YORK, A CORPORATION OF NEW YORK

VISIBLE INDEX

Application filed February 21, 1930. Serial No. 430,186.

This invention relates to a visible index and is concerned particularly with a portable type composed of a plurality of interconnected sections variable in number whereby 5 additional cards may be made available conveniently when and as required. More particularly, the invention has for its object to provide a portable index, the sections of which are hingedly interconnected and adapted 10 to be brought together in a manner comparable to a book thereby affording ready access to the cards, convenient condition for use when laid on a flat surface and compactness and protection for the cards when the 15 sections are folded together.

In accordance with the invention it is proposed to provide two tray sections for index cards which may be hingedly interconnected adapting them to be folded together when not 20 in use and extended apart and laid flat to expose the banks of cards when in use. The invention also provides for the introduction at the hinged line of the first two named tray sections of an additional section formed on 25 its reverse faces with accommodations for banks of cards so that when the said additional section is hingedly interconnected to the two first named tray sections the capacity of the index is doubled without modifying 30 the general relationship of any of the sections or increasing materially the bulk of the entire index. More specifically, the desired relationship with the additional section introduced is obtained and convenient operation 35 retained through the provision of a double hinge interposed operatively between the additional section and each of the two first-named sections thereby assuring complete flexibility.

The invention will be described in detail in connection with the embodiment illustrated in the drawings, in which:

Figure 1 is a view in perspective of the 45 improved index showing two trays hingedly interconnected.

Figure 2 is a view in end elevation of the tray shown in Figure 1.

Figure 3 is a view in perspective showing 50 one side of the additional double tray which

is adapted for insertion between the two trays shown in Figure 1.

Figure 4 is a view in perspective showing the double hinge interposed between the double tray shown in Figure 3 and the two trays shown in Figure 1.

Figure 5 is a view in end elevation of the expanded index illustrated in Figure 4 with the sections in position for use on a flat surface.

The invention is not limited to any particular type of tray or card mounting since any type that lends itself to incorporation in tray sections which may be related in accordance with the principle disclosed herein may be used. As illustrated in Figure 1 there are shown two metal trays *a*, *b*, each one of which has accommodations on one side for card holders illustrated as bars *b'* in which are hingedly mounted, respectively, the cards *b*² adapted to occupy the usual relationship. Similar card holders and cards may, of course, be mounted in the other section *a*. Each section *a*, *b*, has along its proximate edge complementary hinge sections *a'*, *b'*, respectively, which when brought together will receive a pintle *c* whereby the two sections *a*, *b*, are hingedly secured together. The connection is such, as will be appreciated from Figure 2, as to permit the two sections to be moved swingably apart about the pintle *c* so that they may lie flat on a flat surface thereby presenting respective cards for convenient use. Conversely, the two sections being similar in outline may be brought together face to face like the covers of a book thereby making for greatest possible compactness when the trays are not in use and affording suitable protection for the cards.

The construction described is such as to permit the expansion of the improved index to the extent at least of doubling the card capacity by the introduction between the two sections *a*, *b*, of a third section such as illustrated in Figure 3. For economy of manufacture it is preferred to form this additional section *d* of two such sections as are illustrated at *a* and *b* in Figure 1, placed back to back and united in an available manner as by welding. Two such sections thus united are

indicated in Figure 3 at d' , d^2 , the resulting section d thereby accommodating banks of cards on each surface. The section d carries hinge lugs d^3 , d^4 , on its inner edge and these lugs may have two hinge members e , f , pivotally attached to them by means of a pintle g . When the two sections a , b , have been disconnected by withdrawing the pintle c they may have pivotally attached to them, respectively, 5 the hinge members e , f , by means of separate pintles e' , f' , passing through the lugs a' , b^3 , respectively, and aligned lugs e^2 , f^2 , on the respective hinge members e , f . When the 10 several hinge elements are thus pivotally interconnected by means of the pintles as described, it will be evident that the center section d is hingedly connected to the outer sections a , b . The use of the double hinge elements permits relative pivotal movement between 15 each one of the sections a , b and d , and the hinge elements to which they may be secured. The expansion of the index thus effected doubles its capacity as will be apparent since a bank of cards may be mounted 20 in each side of the center section d . The use of any of the cards remains as convenient as described in connection with the two sections a , b , in Figure 1 since the pivotal interconnection permits the sections 25 a , b , to rest flat on a flat surface while one or the other of the bank of cards in the center section d likewise is presented to view 30 in flat working position as clearly appears

from Figure 5. When all of the sections are folded together the index is very compact having its thickness only affected to the extent of the thickness of the center section d while the superficial area is no greater.

The flexibility in capacity thus afforded is 70 of importance to the user since a greater or lesser number of parts may be used as may be needed. Since the tray sections are rigid elements they permit convenient handling of 75 the entire index and its portable and compact nature enables it to be placed within a very small space such as a desk drawer or cabinet.

Changes in the character of the trays and 80 card supports and the form and type of pivotal interconnections may be made without departing from the spirit of the invention so long as the general principle disclosed is retained.

What I claim is:

An expandible visible index comprising 85 card trays having complementary hinge members secured to their edges, respectively, an intermediate card tray having two hinge members secured pivotally along one edge, 90 said members being complementary to the first named hinge members, respectively, and removable means to secure the second named hinge members pivotally to the first named hinge members, respectively.

This specification signed this 18th day of 95 February A. D. 1930.
